UNITED STATES PATENT OFFICE.

JOHN S. LENNOX, OF PITTSFIELD, MASSACHUSETTS, ASSIGNOR, BY MESNE ASSIGNMENTS, TO THE UNION SWITCH AND SIGNAL COMPANY, A CORPORATION OF PENNSYLVANIA.

INDUCTIVE OR TRANSFORMER BOND.

1,085,616.

Specification of Letters Patent.

Patented Feb. 3, 1914.

Application filed March 6, 1912. Serial No. 681,943.

To all whom it may concern:

Be it known that I, JOHN S. LENNOX, a subject of the King of Great Britain, residing at Pittsfield, in the county of Berkshire and State of Massachusetts, have invented certain new and useful Improvements in Inductive or Transformer Bonds, of which the following is a specification.

One feature of an inductive bond or transformer bond embodying my invention is the provision of an inclosing casing or shell of magnetic material, which casing or shell serves as a portion of the magnetic circuit for the bond.

15 I will describe one form of inductive bond and one form of transformer bond embodying my invention and then point out the novel features thereof in claims.

In the accompanying drawings, Figure 1 is a view showing in side elevation, with the inclosing casing in section, an inductive bond embodying my invention. Fig. 2 is an end view, partially sectioned, of the bond shown in Fig. 1. Fig. 3 is a view showing in 25 cross section a transformer bond embodying my invention.

Similar reference characters refer to similar parts in each of the views.

A bond embodying my invention is intended, primarily, for use in the track of electric railways when both track rails are included in the propulsion current circuit and are divided at points by insulation to form block sections for signaling purposes. 35 The bonds are located along the trackway adjacent the points of insulation, and are employed for conducting the propulsion current around these insulation points.

Referring now to the drawings, 10 designates an inclosing shell or casing of magnetic material, preferably of cast iron. This casing is provided with a cap 11, also of magnetic material. Within the casing 10 is a core 12 of magnetic material, preferably 45 of laminated soft iron, the laminations being arranged parallel with the longer axis of the core. The winding for the bond is placed upon this core. After the bond is assembled, it is generally poured full of a 50 waterproof insulating compound which makes the whole interior of the bond a solid mass and holds the winding and central core in place. For introducing this compound a hole may be provided in one of

the heads which hole is afterward closed 55 by a pipe plug, as shown at 21 in Fig. 2.

The core may be held in position within the casing in any suitable manner; for example, as shown in Figs. 1 and 2 it is secured by means of angle members 18 bolted 60 to the core and to the casing; as shown in Fig. 3 it is secured by means of the windings on the core; the leads thereto, and the insulating compound. In each of the modifications here shown, one end of the core is in 65 contact with the bottom of the casing and an air gap is provided between the other end of the core and the cap 11. It will be understood however that other air gaps may be provided, or no air gap at all; the use or 70 non-use of air gaps being dependent upon the conditions under which the bond is used. The air gaps may be adjustable or non-adjustable. As shown in Fig. 3 the air gap is non-adjustable, the space which forms the 75 gap being filled with a packing of non-magnetic material 20 such as press board. As shown in Figs. 1 and 2, the air gap 15 is rendered adjustable by means of a screw plug 14 in the cap 11 opposite the end of 80 the core; it is of course understood however that other means may be provided for rendering the air gap adjustable.

The winding or windings for the bond comprise a suitable conductor or conductors 85 wound upon the core 12, the terminals being carried out through suitable holes in the casing or cap or both. It will be seen that the magnetic circuit for this winding or windings comprises the core 12, the casing 90 10 and cap 11. Hence in a bond embodying my invention the inclosing shell or casing is included in the magnetic circuit for the bond, thereby reducing the size and cost 95 of the bond for a given capacity.

In the form of inductive bond illustrated in Fig. 1, the winding, which is shown diagrammatically, comprises two conductors 13 wound in close inductive relation with each other and in opposite directions, one end of 100 one conductor being joined with the corresponding end of the other conductor at the point 16; a suitable conductor C is connected with the winding at the point 16. It will be clear from the drawing that if 105 equal currents flow into the winding from A and B in the directions indicated by the arrows and out at C, the magnetic flux

caused by these two currents will be balanced and consequently the casing and core will not be magnetized. But if current flows into the winding at A and out at B, or vice versa, the core and casing will be magnetized and if this current is alternating its flow will be opposed by the impedance of the magnetic circuit.

In Fig. 3 I have shown, in addition to the 10 conductors 13, a secondary winding D—E, which may be connected with a source of current, a relay, or which may be used for any other purpose which may be desirable.

Although I have herein shown only two 15 arrangements of winding for a bond embodying my invention, it is understood that any arrangement of winding or windings may be employed in accordance with the circumstances under which the device is employed.

Since the bond is used in connection with alternating current, the casing 10 and cap 11 are preferably provided with a slot 17 extending from about the center of one end 25 to about the center of the other end, to prevent the shell from acting as a short circuited secondary for the alternating current. This slot 17 is preferably filled with a suitable non-conducting material which 30 will render the shell water-proof.

Although I have herein shown and described only two forms of bond embodying my invention, it is understood that various modifications may be made therein within 35 the scope of the appended claims without departing from the spirit and scope of my invention.

I do not claim the adjustable air gap 15 shown herein, this feature being the subject-matter of an application by Laurence A. 40 Hawkins, filed May 17, 1913, Serial No. 768,302, for inductive bonds.

Having thus described my invention, what I claim is:

1. An inductive or transformer bond comprising an inclosing casing of magnetic material, a core of magnetic material contained within the casing one end of the core being in contact with the casing and the other end being separated from the casing by an air 50 gap, and a winding on the core, the magnetic circuit for the winding comprising the core, the casing and the air gap.

2. An inductive bond comprising a cylindrical casing of magnetic material, a 55 laminated core axially arranged within said casing and a double winding on said core, each portion of the winding consisting of a conductor which enters at one end of the casing, passes around the core and passes 60 out through the other end of the casing.

3. An inductive or transformer bond comprising an inclosing casing of magnetic material, a core of magnetic material within 65 the casing, an air gap between the casing and the core, and a winding on the core the magnetic circuit for the winding comprising the core, the casing and the air gap.

In testimony whereof I affix my signature in presence of two witnesses.

JOHN S. LENNOX.
